(57) **CLAIM**

The ornamental design for a portion of a combined lighting fixture and hanger, as shown and described.

DESCRIPTION

FIG. 1 is a cut away bottom perspective view of a portion of a combined lighting fixture and hanger showing our new design;

FIG. 2 is an end elevational view thereof;

FIG. 3 is a side elevational view thereof, the other side being a mirror image;

FIG. 4 is a bottom plan view thereof; and

FIG. 5 is a top plan view thereof.

FIG. 6 is a bottom perspective view of an alternative embodiment of a portion of a combined lighting fixture and hanger showing our new design;

FIG. 7 is an end elevational view thereof;

FIG. 8 is a side elevational view thereof, the other side being a mirror image;

FIG. 9 is a bottom plan view thereof; and,

FIG. 10 is a top plan view thereof.

FIGS. 1-10 are broken away to indicate indeterminate length. The broken line showing of a fluorescent lamp in FIGS. 5 and 10 is for illustrative purposes only and form no part of our claimed design. The broken lines immediately adjacent the shaded areas in FIGS. 5 and 10 represent the bounds of the claimed design; the region within these broken lines forms no part of our claimed design.
